US0D1018549S

(12) **United States Design Patent** (10) **Patent No.:** **US D1,018,549 S**
(45) **Date of Patent:** **** Mar. 19, 2024**

(54) **HOUSING MODULE FOR AN ELECTRONIC DEVICE**

(71) Applicant: **Apple Inc.**, Cupertino, CA (US)

(72) Inventors: **Jody Akana**, Los Altos Hills, CA (US); **Molly Anderson**, San Francisco, CA (US); **Bartley K. Andre**, Palo Alto, CA (US); **Shota Aoyagi**, San Francisco, CA (US); **Anthony Michael Ashcroft**, San Francisco, CA (US); **Marine C. Bataille**, San Francisco, CA (US); **Jeremy Bataillou**, San Francisco, CA (US); **Markus Diebel**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Julian Jaede**, San Francisco, CA (US); **Duncan Robert Kerr**, San Francisco, CA (US); **Peter Russell-Clarke**, San Francisco, CA (US); **Benjamin Andrew Shaffer**, San Jose, CA (US); **Mikael Silvanto**, San Francisco, CA (US); **Sung-Ho Tan**, Vienna (AT); **Clement Tissandier**, San Francisco, CA (US); **Eugene Antony Whang**, San Francisco, CA (US); **Rico Zörkendorfer**, San Francisco, CA (US)

(73) Assignee: **Apple Inc.**, Cupertino, CA (US)

(**) Term: **15 Years**

(21) Appl. No.: **29/897,286**

(22) Filed: **Jul. 13, 2023**

Related U.S. Application Data

(63) Continuation of application No. 29/858,401, filed on Oct. 31, 2022, now Pat. No. Des. 993,253, which is a continuation of application No. 29/801,748, filed on Jul. 30, 2021, now Pat. No. Des. 968,412, which is a

continuation of application No. 29/768,801, filed on Feb. 1, 2021, now Pat. No. Des. 926,771, which is a continuation of application No. 29/662,274, filed on Sep. 4, 2018, now Pat. No. Des. 909,388.
